UNITED STATES PATENT OFFICE.

LOUIS JAGIELKY, OF NEW YORK, N. Y.

PROCESS OF ORNAMENTING GOLD SURFACES.

SPECIFICATION forming part of Letters Patent No. 407,953, dated July 30, 1889.

Application filed March 8, 1889. Serial No. 302,522. (No model.)

To all whom it may concern:

Be it known that I, LOUIS JAGIELKY, of the city, county, and State of New York, a citizen of the United States, have invented certain 5 new and useful Improvements in Processes of Ornamenting Gold Surfaces, of which the following is a specification.

This invention relates to an improved process of ornamenting gold plates in a rich and 10 artistic manner; and the invention consists of a process of ornamenting gold plates, composed of the following successive steps: first, producing the raised ornamental design on the surface of the plate by cutting out the 15 stock around the same; secondly, matting the cut-out ground; thirdly, gilding the raised and matted work; fourthly, polishing the surface of the raised parts, and, finally, decorating the raised parts with precious stones and 20 engraving the same.

In the accompanying drawings, Figures 1, 25 3, and 5 represent front views of a watch-case cap shown in the different stages of ornamentation according to my improved process; and Figs. 2, 4, and 6 are vertical transverse sections of Figs. 1, 3, and 5, respectively.

Similar letters of reference indicate corresponding parts.

In carrying out my invention the gold plate 30 to be ornamented—such as is used for watch-cases, lockets, rings, bracelets, and other jewelry—is first engraved with the outline of the design, as shown in Fig. 1. The metal is then cut away around the design, so as to produce 35 the same in raised part on the plate and inter-

gral with the same. The ground around the raised parts is then matted, as shown in Fig. 3, and the entire surface gilded by electro-deposition or otherwise. The surfaces of the raised parts are next polished by means of 40 suitable buffing-wheels and the raised parts ornamented by inserting precious stones into the same in the usual manner, after which the raised parts are finished around the stones by engraving them as shown in Fig. 5. In 45 this manner a very ornamental character is imparted to the surfaces of gold jewelry of all kinds and the same finished in a very elaborate and artistic manner.

Having thus described my invention, I claim 50 as new and desire to secure by Letters Patent—

The process herein described of ornamenting the surfaces of gold plates, which consists of the following steps successively performed: first, producing a raised design by cutting 55 out the stock around the design; secondly, matting the cut-out ground; thirdly, gilding the entire surface; fourthly, polishing the surface of the raised parts, and, lastly, inserting precious stones into the raised parts 60 and engraving the surface of the raised parts, substantially as set forth.

In testimony that I claim the foregoing as my invention I have signed my name in presence of two subscribing witnesses.

LOUIS JAGIELKY.
